UNITED STATES PATENT OFFICE.

JOSEPH J. MARIOTTI, OF CHICAGO, ILLINOIS, ASSIGNEE TO DAPRATO STAUTARY COMPANY, OF CHICAGO, ILLINOIS, A CORPORATION OF ILLINOIS.

SAFE-DOOR CONSTRUCTION.

Application filed March 12, 1925. Serial No. 14,865.

To all whom it may concern:

Be it known that I, JOSEPH J. MARIOTTI, a citizen of the United States, residing at Chicago, in the county of Cook and State of Illinois, have invented certain new and useful Improvements in Safe-Door Constructions, of which the following is a specification.

This invention pertains to door operating mechanism and more particularly to a mechanism for simultaneously operating double doors of safes and the like.

Heretofore, safes and the like have been provided with double doors of substantially the same size adapted to engage one another tightly when in a closed position. Both doors in this construction are independently operable, that is to say, either door might be opened and closed without movement of the other door, but for some purposes, such as for altar safes, where it is desired to retain aesthetic features, and for other purposes where the mechanical features alone are most important, it is desirable to have both doors open simultaneously.

It is therefore a primary object of my invention to provide a simple and inexpensive, but efficient and reliable mechanism for simultaneously opening both doors of a safe or other structure.

Another object is to provide a mechanism for simultaneously opening double doors of safes of such nature and so constructed that the safe doors may be readily opened by pulling upon the key, knob, or other projection provided, and wherein only one such means providing a hand hold may serve to open both doors.

Other objects and novelties of my invention will appear from the description and claims and from the drawing in which:

Fig. 1 is a front elevation of a safe construction showing one form of my invention applied thereto and,

Figs. 2 and 3 are plan views of the mechanism taken along the line II—II of Fig. 1.

The safe consists of suitable frame members 2, 3, 4, and 5, forming the body and a pair of doors 6 and 7 respectively pivoted or hinged at 8, 9, 10, and 11 in the frame members 3 and 5, although they may be otherwise hinged or pivoted in the frame members 2 and 4 in any suitable manner as will be obvious. The doors are adapted to

engage in slightly overlapping relation along a line substantially midway between the frame members 2 and 4 as shown at 12.

The hinge members 8 and 10 are preferably made slightly longer than the opposite hinges of their respective doors and are journaled or hinged in the frame at 13 and 14. A compartment or space 15 is provided into which the hinge members 8 and 10 project in order to provide operating room for cam members 16 and 17 and a connecting toggle bar 18 extending between the cam members.

Each cam member is provided with a slot 19 extending substantially half-way through it, of a width to permit ready passage of the toggle bar 18 therein, with a pivot pin 20 adapted to pivotally secure the end of the toggle bar 18 and a set screw 21 for securing it to the hinge members 8 and 10. The cam members 16 are preferably secured on the hinge pins to dispose the pivot pins 20 on opposite sides of a plane passing through the axes of the two bottom hinges, or, in other words, the pivot pins are so disposed with respect to one another that planes passing through the axes of each hinge and its respective pivots will be angularly unsymmetrical or angularly displaced, one from another. This construction is clearly illustrated in Figs. 2 and 3.

Fig. 2 shows the mechanism as it is preferably arranged when the doors are in closed position as indicated in dotted lines, while Fig. 3 shows the mechanism as it would appear when the doors are open. It is believed that the operation of the mechanism will be readily apparent from the foregoing.

I claim:

1. In combination, a pair of safe doors cooperatively engageable at one vertical edge when in closed position, upper and lower hinge members connected to said doors adjacent their opposite vertical edges, the lower hinge member of each door having a portion projecting beyond the lower edge of its respective door, a member provided with an abutment shoulder, on and adjustably connected to each of said projecting portions, a pivot pin on each member adjacent the shoulder thereon, and a bar pivoted at its ends to said pivot pins, said pins being so located on said members as to lie on substantially opposite sides of the line of

- centers of the door hinges when the doors are in one of their two extreme positions and said shoulders, pins and bar being constructed and arranged so that opening and closing movements of one door will correspondingly open and close the other door and so that opening movements of the doors beyond a predetermined position will be limited by engagement of one of said shoulders with the adjacent end of the bar.
2. In combination, a pair of parallel spaced door frame members, a pair of safe doors cooperatively engageable at one vertical edge when in closed position, upper and lower hinges adjacent the opposite vertical edge of each door and pivoted in said frame members, a cam member secured to each lower hinge between the lower edge of its door and the adjacent frame member, a shoulder on each cam member projecting generally in the direction of the axis of the adjacent hinge and on both sides of said hinge along a diameter thereof, a pivot pin on each cam member adjacent the shoulder thereon and a rigid bar pivoted to said pivot pins at its ends, said pins being so located on said members as to lie on substantially opposite sides of the line of centers of the door hinges when the doors are in one of their two extreme positions and said cam members, pivot pins and bar being constructed and arranged so that opening movements of the doors beyond a predetermined position will be limited by engagement of one of
- said shoulders with the adjacent end of the bar.
3. In combination, a pair of safe doors each pivotally hinged at one vertical edge and cooperative at its other vertical edge with the corresponding vertical edge of the other door when said doors are in closed position, a hinge member secured to each door and projecting from corresponding horizontal edges of the doors in substantial alignment and substantially coincident with the pivotal axes of the doors, a collar adjustably secured on each member for swinging movements therewith, a pivot pin on each collar eccentric of the axis of the member to which the collar is attached, a shoulder on each collar adjacent the pin thereon and on a projection of a diameter of the hinged member, and a rigid bar pivotally connected to said pins at its ends, said pins being so located on said members as to lie on substantially opposite sides of the line of centers of the door hinges when the doors are in one of their two extreme positions and said pins being so relatively positioned with respect to one another and to the axes of said members that opening or closing movements of one door will open or close the other door simultaneously and said shoulders each adapted to engage one side of an end of the bar to limit the extent of opening movement of the doors.

JOSEPH J. MARIOTTI.
